UNITED STATES PATENT OFFICE

2,037,239

SPARK PLUG

James W. Jean, Altadena, Calif.

Application March 10, 1933, Serial No. 660,256

4 Claims. (Cl. 123—169)

My invention relates to improvements in spark plugs characterized by the use of three readily separable assembled units, one an outer shell which is secured through the wall of the combustion chamber of an internal combustion engine and carrying or forming an outer electrode, second an insulator which is detachably secured in said shell, said parts having a gas tight joint therebetween, and third a central or inner electrode which is held in juxtaposition to the outer electrode and which is detachably secured to said insulator by a gas tight joint, said parts being readily combined into a single structure or separated and which are effectively protected from short circuiting and from becoming over heated when used. Among the advantages attained by my invention may be mentioned the following:

1st. A spark plug which will withstand extremes of heat and cold without cracking, breaking or leaking gas. 2nd. A substantially unbreakable and indestructable spark plug which has a maximum of efficiency, coupled with long lasting qualities. 3rd. A spark plug that permits of quick and easy dismantling of parts for quickly inspecting and cleaning and which assures quick and positive reassembly of parts by skilled or unskilled labor in an effective manner and with gas tight joints, without breaking. 4th. A spark plug that assures a clean spark plug and delivery of all of the current to the spark plug at all times, thus resulting in a fat spark as the current jumps across the spark gap and assurance against a foul plug, and 5th. The complete suppression of leakage which otherwise tends to cause static in radio sets used in motor vehicles.

A common source of trouble with spark plugs results from a coat of carbon deposited on the insulator in the casing. This carbon deposit thereby forms a pathway for the current that is of much less electrical resistance than the gap jump. Since electricity follows the line of least resistance, the current takes this path over the carbon layer, diverting part or all of the current away from the gap. This results in a weakened spark or no spark at all with consequent loss of power, rapid accumulation of carbon and complete failure of the cooperating cylinder and piston. Another source of trouble with spark plugs results from leaking of water around the plug or through the parts of the plug, this being particularly true in cold and wet weather. These objections are entirely overcome by my improvement.

To these ends my invention comprises the features of construction and combination of parts hereinafter described and claimed.

In the accompanying drawing forming part of this specification, Fig. 1 is a vertical section of my invention on an enlarged scale, part of the interior structure being shown in full side elevation and part of said structure being shown broken away and in section; Fig. 2 is a full side elevation of my invention, approximating normal or full size; Fig. 3 is a side elevation of the insulator separate from the remaining cooperating parts; Fig. 4 is a full side elevation of the inner electrode; Fig. 5 is a vertical central section of the bushing, and Fig. 6 is a cross section taken on line 6—6 of Fig. 1.

In the drawing A indicates the metallic shell of my improved spark plug which is externally threaded at 10 on its lower end to screw into the usual threaded spark plug hole in the wall 20 of the combustion chamber of an internal combustion engine and which is externally shouldered on its upper end at 11 for engagement by a wrench to assist in screwing and tightening the plug in the cylinder wall. Internally the 25 shell is passaged longitudinally at 13, the upper portion being larger in diameter than the lower and internally threaded at 14 for engagement by the external threads 15 of a bushing B to be hereinafter described. The upper and lower 30 sections of the passage 13 are joined by a downwardly and inwardly tapering shoulder 16 which forms an annular seat above which an external shoulder 17 on the insulator element C is adapted to rest with a washer 18 therebetween. The 35 lower end of the shell is provided with the usual outer electrode terminal 19 which is directed inwardly in juxtaposition to the lower extremity of the inner electrical terminal D to be hereinafter described. In use the shell is screwed 40 tightly into the spark plug opening of the internal combustion engine with the spark gap in or adjacent to the combustion chamber so as to function in the usual manner.

The insulating element C which is composed of porcelain or any other suitable insulating material has a cylindrical body 20 formed with a long gradually tapering lower end 21 having said slightly curved annular shoulder 17 joining their surfaces. The upper portion of the insulating element resembles a cylindrical stem 22 of less diameter than and joined to said cylindrical body 20 by a slightly curved upper seat 23. The cylindrical surface of the stem 22 is provided with a plurality of longitudinal 45 50 55

circumferentially spaced dead air channels 24 for absorbing heat from the metallic and porcelain parts of the spark plug. Internally the insulating element C is centrally passaged at 25 throughout its length to receive and hold the inner electrode D. In use the insulating element and shell are assembled with the annular shoulder 17 resting above the seat 16 and with the washer 18 between to assist in producing a gas tight joint while the lower tapering end 21 projects downwardly in the main passage of the shell.

The portion of the insulator 21, within the metallic shell A or firing chamber of the plug 15 has a glazed outer surface which reduces tendency for carbon to collect thereon, and the portion 22 outside of the firing chamber, that is above said shell and within the insulating cap E has an unglazed outer surface which tends to 20 retard conductivity of static producing electrical energy.

The bushing B is screwed down with its lower upwardly and inwardly tapering annular end 26 pressing downwardly against the annular seat 23 for holding the insulating element in leak tight rigid connection with the shell. This bushing has a cylindrical longitudinal passage 27 above its lower end 26, which fits freely over the stem 22 of the insulating element. The outer surface of 30 the bushing below its upper ends is shouldered at 28 for engagement by a wrench to turn and tighten the bushing. The upper end of the bushing resembles a collar 29 for the purpose to be hereinafter described.

35 The inner electrode D resembles a rod which is thrust down through the passage 25 in the insulating element and which is formed with a downwardly tapering threaded head 30. This threaded head is adapted to screw into a downwardly tapering threaded socket 31 (see Fig. 1) in the upper end of the insulating element C to tightly secure the inner electrode therein. Above the threaded head 30 is a circular shoulder 32 and above said shoulder is an upwardly tapering 45 threaded nipple 33 constituting an inner electrical circuit engaging terminal.

E is an insulating cap resembling a thin shell composed of composition resembling high fire test "Bakelite" or any other suitable electrical insulating and heat absorbing moisture proof 50 material. This cap fits down snugly over the annular collar 29 on the bushing to produce a tight joint and has a central opening 34 in its upper end through which the inner electrode D 55 including its head 30 is thrust downwardly and screwed tightly home in the insulating element C. In this position the annular shoulder 32 clamps the insulating cap tightly down over the collar on the bushing and assists in sealing the upper end of the bushing B, insulating element C and inner electrode D from water or other liquid. In this manner the parts of the spark plug are 60 thoroughly protected against leaking and short circuiting. A thin packing or jacket 35 of cork or other suitable heat absorbing and electrical insulating material is placed snugly over the stem 22 of the insulating element and within the insulating cap E and in conjunction with the channels 24 serves to absorb heat from within the 65 spark plug and electrically insulate the parts, thus serving to reduce the hazard of the material constituting the insulating element C from cracking and rendering the upper end of the spark plug substantially cool at all times. Also 70 the material 35 being comparatively soft acts as 75

a buffer for protecting the fragile insulating element C from impact.

When desired a circuit terminal (not shown) of the internal combustion engine may be clamped on the collar 32 of the inner electrode by 5 a cap screw 36 which is threaded over the nipple 33 of the inner electrode or the cap screw can be turned down securely over the threaded nipple 33 and a circuit terminal of usual construction engaged thereover in a circular channel 37 which 10 is provided for that purpose.

In use the inner electrode assembly can be removed from the outer electrode shell while the shell is screwed in or removed from the engine by unscrewing the bushing B. The lower tapering 15 surface 21 of the inner electrode insulator C can then be cleaned and the parts quickly reassembled. If it is desired to clean the inner electrode it can be done when dismantling the shell and insulating element or independently thereof 20 by unscrewing and removing it from the insulating element and after cleaning replacing. While the inner electrode is removed the insulating cap E and heat absorbing element 35 can be removed or if the shell A and insulator C have 25 been dismantled the bushing can be lifted off of the insulator and the parts inspected, wiped and reassembled quickly and effectively. Thus it is apparent my improved spark plug provides an inner electrode which can from time to time be 30 easily and quickly examined, cleaned and replaced with or without disturbing any of the other parts of the spark plug or without removing the plug from the internal combustion engine. This is a distinct advantage and promotes 35 the effectiveness of the device. Also the entire inner electrode assembly can be removed at any time without disturbing the outer electrode shell, which is an advantage.

In accordance with the patent statutes, I have 40 described the principles of operation of my invention, together with the construction thereof which I now consider to represent the best embodiment thereof, but I desire to have it understood that the construction shown is only illustrative and that the invention can be carried out by other means and applied to uses other than those above set forth within the scope of the following claims.

Having described my invention what I claim 50 as new and desire to secure by Letters Patent is:

1. A spark plug, comprising, in combination, an outer electrode shell having an electrode terminal on its lower end, an insulator in and having a stem projecting above said shell, said stem being 55 channeled longitudinally on its upper end to produce air pockets, fastening means for holding said insulator in said shell, a cap of insulating material placed over the upper end of said insulator and fastening means, a heat absorbing 60 jacket between said cap and insulating stem whereby conductivity of heat from the stem is retarded, and an inner electrode rod removably thrust through said insulator and cap with its lower end in juxtaposition to said outer electrode 65 terminal and having means by which the upper end of said rod is detachably secured to said insulator and said cap is sealed over said insulating stem and fastening means.

2. A spark plug, comprising, in combination, 70 an outer electrode shell having an electrode terminal on its lower end, an insulator in said shell, having an annular shoulder and a stem projecting above said shoulder and shell, said stem being passaged longitudinally, fastening means engag- 75

ing said insulator above said shoulder and in threaded engagement with said shell, a moisture proof cap of low heat conductivity placed over said stem and fastening means and passaged longitudinally, an inner electrode rod removably extending through the passage in said insulator and cap with its lower end in juxtaposition to said outer electrode terminal and having a head piece screw threaded into said insulator to removably hold the inner electrode in said insulator and formed with an annular shoulder adapted to removably engage and hold said cap over said stem and fastening means, and means occurring between the cap and the insulator for permitting a circulation of air therebetween.

3. A spark plug for internal combustion engines, comprising, a metallic shell adapted to be secured within the engine head, an electrode carried by said shell, an insulating member extending into the shell and secured thereto and sealed therein at a point intermediate its ends, and having a projecting stem channeled longitudinally, whereby a portion of the insulator will be within the firing chamber of the engine and the channeled portion will be outside the firing cham-

ber, an electrode carried by the insulator, and a cap formed of dielectric material and secured over the portion of said insulator outside the firing chamber, and means occurring between the cap and the stem of said insulator for permitting a circulation of air therebetween.

4. A spark plug for internal combustion engines, comprising, a metallic shell adapted to be secured within the engine head, an electrode carried by said shell, an insulating member extending into the shell and secured thereto and sealed therein at a point intermediate its ends and having a projecting stem channeled outwardly whereby a portion of the insulator will be within the firing chamber of the engine and its stem will be outside the firing chamber, an electrode carried by the insulator, a cap formed of dielectric material and secured over the stem portion of said insulator outside the firing chamber, means occurring between the cap and the insulator for permitting a circulation of air therebetween, and heat insulating lining disposed between the cap and the insulator.
